PORTABLE SERVING BAR

Larry N. Wynveen, Sheboygan, and Stephen J. Jambretz,
Jackson, Wis., assignors to Thanco, Inc.

Filed Dec. 23, 1971, Ser. No. 211,833

Term of patent 14 years

Int. Cl. D7—99

U.S. Cl. D7—71

FIG.1

FIG.5

FIG. 1 is a perspective view of a portable serving bar embodying our new design;

FIG. 2 is a right end elevation thereof, the left end being a mirror image;

FIG. 3 is a top plan view thereof on an enlarged scale;

FIG. 4 is a front elevation thereof of FIG. 3; and

FIG. 5 is a rear elevation thereof of FIG. 3.

The bottom is essentially plain and unornamented.

We claim:

The ornamental design for a portable serving bar, substantially as shown and described.
